UNITED STATES PATENT OFFICE.

CHARLES TRAVIS BRIAR, OF SAN DIEGO, CALIFORNIA.

STEAM GENERATOR.

Application filed October 25, 1924. Serial No. 745,905.

This invention relates to steam generators and more particularly to a circulating water level type, combination water tube and fire tube steam generator, designed primarily for automotive use although, of course, the invention is not limited to any particular use.

An object of the invention is to provide a steam generator having an improved 10 design of burner constituting a part thereof, and in which generator all available heat units are utilized, using the heat both in downward and upward flow and utilizing the rising heat to assist in vaporizing the 15 incoming raw fuel.

A further object is to so construct the boiler in relation to its burner as to prevent extinguishing of the burner in the event of leakage in the boiler.

20 A further object is to provide a generator of the character described which utilizes the circulation and keeps all foreign and scale forming matter in suspension so that the apparatus will not foul and will generate 25 steam very rapidly.

A further object is to provide a generator in which all foreign heavy particles will accumulate in the bottom of a mud drum where they can be blown off or otherwise 30 removed from time to time.

35 A further object is to provide a steam generator which comprises a small compact unit and which will utilize to the maximum degree the heat units of the fuel employed, thus resulting in an economy of operation and also in increased efficiency over generators commonly employed.

With these and other objects in view, the 40 invention consists in certain novel features of construction and combinations and arrangements of parts, which will be more fully hereinafter described and pointed out in the claims.

In the accompanying drawings—

45 Figure 1 is a view in longitudinal section through my improved steam generator;

Figure 2 is a plan view of the generator;

Figure 3 is a view in horizontal section on the line 3—3 of Figure 1.

50 A represents the casing of my improved generator which is circular in form horizontally and which is of greatest diameter at its base, as indicated at 1. The intermediate portion 2 of the casing A is appreciably 55 smaller in diameter than the base 1, and the upper portion of the casing 3 is of apprecia-

bly less diameter than the intermediate portion 2.

In the intermediate portion 2 I locate my improved boiler 4 which is of the combined 60 water tube and fire tube type with all of the tubes running vertically. In the center of the boiler I provide a flue 5, and around the flue I provide a circular series of fire tubes 6. It will be noted that the flue 5 is of ap- 65 preciably greater diameter than the tubes 6 and constitutes in effect a vertical burner tube, as will more fully hereinafter appear.

The lower portion of the casing A constitutes a combustion chamber 7, and the upper portion 3 of the casing A constitutes a burner 8. An outlet chamber 9 is formed between the top of the boiler 4 and the casing section 3 and communicates with an outlet flue 10.

75 Within the lower section 1 of the casing A a circular or annular mud drum 11 is provided and connected by a circular series of tubular legs 12 with the lower portion of the boiler 4. In the combustion chamber I provide a vertical series of horizontally arranged generating coils 13. These coils 13 are spiral in form and have their inner ends connected by tubes 14 with the bottom of the boiler 4 and have their outer ends connected 80 by tubes 15 with the legs 12.

85 The circulation is upward through the tubes 14 into the boiler 4, thence down through the legs 12 and through the tubes 15 into the coils 13. Hence, foreign matter which may accumulate in the water will drop down through the legs into the mud drum 11 and can be discharged from time to time in any approved manner.

90 The superheated steam take-off pipe 95 extends through the fire tubes 6.

In the bottom of the combustion chamber 7 I provide a spiral superheating coil 16, the inlet end of which constitutes a tube 17 projecting through the boiler 4 into the 100 chamber 9 and has a bend 18 at its upper end communicating with the steam space in the boiler. A pipe 19 constituting the outlet of the spiral superheating coil extends up through the boiler 4 and out through the 105 side of the casing section 2, as indicated at 20.

110 The large central flue of the boiler is connected with the interior of the burner casing 3 by a coupling sleeve 21 which also functions as a wall around which the liquid fuel 22 of the burner is located. This liquid

2
fuel is supplied through a passage 23 controlled by an automatic float or other form of valve 24 so as to maintain the proper liquid fuel level around the outside of the sleeve 21. Inside of the burner casing 3 a vertically disposed tube 25 is provided and is spaced from the walls of the casing section 3 by lugs or arms 26.

A suitable deflector 27 is provided in the sleeve 21, and centrally located and supported in any approved manner for a purpose which will hereinafter appear.

28 represents an air inlet which is formed in the top and centrally of the casing section 3, and it is to be understood that a forced draft of air will enter at this opening 28 and may be controlled in any desired manner and connected with any suitable source of supply.

20 An igniting means, as, for example, a spark plug 29, is secured in the casing section 3 and communicates with the liquid fuel level compartment so that when a spark is formed it will ignite the fuel.

25 It will be noted that the fuel space in the burner chamber is annular and is in line with the space between the tube 25 and the inner wall of the burner casing so that when the fuel is ignited the flame will be directed 30 upwardly outside of the tube 25 and as it comes in contact with the downward draft of air it will be commingled with the air forced downwardly through the tube 8, through the sleeve 21 and be deflected by 35 the deflector 27 so as to direct the heat against the walls of flue 5 and be discharged downward against the generator coils 13 and the superheating coil 16. The flow of heat and gases will then be directed upwardly 40 through the fire tubes 6 into the chamber 9 and thence to the outlet flue 10.

It will thus be noted that the highest temperature is in the combustion chamber 7 so that the coils will be rapidly heated and, due 45 to the circulation above described, steam will be rapidly generated, and as it is generated it will pass through the bend 18, tube 17 and superheating coil 16 to be superheated to the temperature necessary, when it will 50 then pass off through the pipe 19 and outlet 20 for use.

Various slight changes and alterations might be made in the general form of the parts described without departing from my 55 invention, and hence I do not limit myself to the precise details set forth but consider myself at liberty to make such slight changes and alterations as fairly fall within the spirit and scope of the appended claims.

60 I claim:

1. A steam generator, comprising a casing, an annular mud drum in the bottom of the casing, legs projecting upwardly from the drum, a boiler communicating with the 65 upper ends of the legs, a large central flue

in the boiler, small fire tubes outside of the flue, said casing having a combustion chamber in its lower portion and an outlet chamber above the boiler with which the smaller fire tubes of the boiler communicate, a sleeve 70 fixed in the flue and projecting up into the upper portion of the casing which constitutes a burner, means for directing fuel around the outside of the upper end of the sleeve, a burner tube fixed in the upper portion of the casing and spaced therefrom and around the outside of which flame from the fuel is directed, and coils in the combustion chamber communicating with the boiler, and said casing having an air inlet opening at its 75 top down which air is directed through the last-mentioned tube, sleeve, and first-mentioned flue into the combustion chamber. 80

2. A steam generator, comprising a casing, an annular mud drum in the bottom of the casing, legs projecting upwardly from the drum, a boiler communicating with the upper ends of the legs, a large central flue 85 in the boiler, small fire tubes outside of the flue, said casing having a combustion chamber in its lower portion and an outlet chamber above the boiler with which the smaller fire tubes of the boiler communicate, a sleeve 90 fixed in the flue and projecting up into the upper portion of the casing which constitutes a burner, means for directing fuel around the outside of the upper end of the sleeve, a burner tube fixed in the upper portion of the casing and spaced therefrom and around the outside of which flame from the fuel is directed, coils in the combustion chamber communicating with the boiler and said casing having an air inlet opening at its 95 top down which air is directed through the last-mentioned tube, sleeve, and first-mentioned flue into the combustion chamber, and a superheating coil in the combustion chamber, one end of said coil communicating with the steam space of the boiler and the other constituting an outlet. 100

3. A steam generator, comprising a boiler, having a combustion chamber below the same, and an outlet chamber above the same, fire tubes communicating with the combustion chamber and the outlet chamber, a relatively large flue in the boiler, means for directing heat through the flue into the combustion chamber and from the latter through the first-mentioned fire tubes, a mud drum around the combustion chamber, legs connecting the drum with the lower portion of the boiler, a vertical series of horizontally positioned spiral coils in the combustion chamber, one end of each coil being connected to a leg and the other to the bottom 115 of the boiler, a superheating coil in the bottom of the combustion chamber connected to the steam space of the boiler, and a burner at the top of the casing. 120

CHARLES TRAVIS BRIAR.
